UNITED STATES PATENT OFFICE.

GEORGE A. WILLIAMS AND ROLAND E. HILL, OF DECATUR, ILLINOIS, ASSIGNEES TO WILLIAMS SEALING CORPORATION, OF DECATUR, ILLINOIS, A CORPORATION OF ILLINOIS.

CAPPING MACHINE.

Application filed October 11, 1926. Serial No. 140,741.

This invention relates to a capping machine for applying caps to the necks or spouts of containers, and in which the caps are provided with a lever which is turned down to fasten the cap upon the said neck or spout.

Caps of this kind are applicable to all classes of containers so long as said containers are provided with a properly shaped neck or spout; and in machines of this class, there is employed a cap holding and lever turning device, and a container elevating device for bringing the spout or neck of the container into engagement with the cap, ready for the lever turning operation; and in the machine herein shown the upward movement of the elevator forces the neck or spout into engagement with the cap and also causes the lever turning device to operate.

The object of the present invention is to provide gripping means for holding the neck or spout while the capping operation is being completed, in order to prevent the crushing of the neck or spout or any displacement of the same; and with this object in view, the invention consists broadly in providing a pair of gripping jaws which are caused to grip the neck or spout and hold the same during the capping and fastening operation, said gripping action being effected by the movement of the container into position to receive the cap thereon.

The invention consists also in certain details of construction and novelties of combination all of which will be fully described hereinafter and pointed out in the claims.

In the drawing forming a part of the specification, Fig. 1 is a face view of a capping machine provided with this improvement; Fig. 2 is a side view of the same; Fig. 3 is a sectional plan view of the gripping jaws and actuating pins and Fig. 4 is a view showing the actuating pins and means for carrying the same.

Referring to the drawings, 10 indicates the standard of a capping machine 11, the hopper for the caps and 12 the mechanism for receiving said caps and turning the levers of the same, for the purpose of fastening the cap upon the neck or spout 13 of a container 14, said container being moved upwardly by means of a container elevator 15 for the purpose of forcing the neck or spout end into

the cap and setting the lever turning device in operation.

The type of cap employed is shown in Williams Patent No. 1,108,959 and a capping machine of this type is shown in Hey, Webber and Le Pere Patent No. 1,458,123. It will be understood, however, that any machine of this general character can be employed and it will also be understood, that although a sheet metal container has been illustrated, the invention is equally as well adapted for glass containers.

Carried by the container elevator, are two gripping jaws 16, 16, arranged in parallel relation with their pivots 17, 17 intermediate their ends.

The forward ends of the jaws are cut out as shown at 18 to embrace the neck or spout 13 and their rear ends are reduced as shown at 19, 19 and shaped for engagement with a centrally disposed pin 20 and two laterally disposed pins 21. These pins 20 and 21 are fixed to a plate or member 22 which in turn is connected to the standard 10 or any other suitable stationary part of the machine. The jaws 16, 16 are preferably pivoted to a horizontal bracket or arm 23 which is a part of the elevator.

The lower end of the pin 20 is tapered as shown at 24 so as to gradually spread the rear ends 19 and force the recessed portions 18 together, and the pins 21 are formed with oppositely inclined portions 25 for the purpose of bringing the ends 19 together and separating the jaws 18.

If desired a spring 26 could be interposed between the jaws to separate the same.

In operation, a cap is slipped into the chuck of the capping device and a container is placed upon the platform or rest of the elevator and the machine in its normal operation causes the container to be moved upwardly until the neck or spout enters the cap and the continued upward movement causes the lever turning mechanism to turn the lever down and fasten the cap upon the neck or spout.

As the container moves upwardly, the jaws 16 are separated at the rear ends and brought together at the ends 18 by the taper 21 of pin 20, contacting with ends 19, and these jaws 16 grip and hold the neck or spout during the entire period when pressure is applied thereto during the capping operation and if this neck

or spout were not so gripped there would be a tendency to push the same down into the head of the container or otherwise impair said spout or neck.

5 Having thus described our invention, what we claim is:

1. In a device of the kind described, the combination with a pair of pivoted jaws, of means for engaging the rear ends of said jaws 10 for bringing their forward ends together, means engaging the rear ends of said jaws for separating their forward ends, said jaws being movable vertically, the opening and closing means being stationary.
- 15 2. In a device of the kind described, a pair of jaws having the outer ends shaped to grip the neck or spout of a container, said jaws being pivoted intermediate their ends, a pin having a tapering end adapted to engage the 20 rear ends of said jaws to move the outer ends into gripping engagement with a neck or spout, and pins having inclined portions for engaging said rear ends for separating the outer ends of said jaws.

3. In a device of the kind described, the combination with a pair of jaws pivoted intermediate their ends, of a pair of pins arranged upon opposite sides of said jaws at the rear ends, and a pin arranged between the rear ends of said jaws, said pins having oppositely inclined portions at the lower ends, said pins and jaws being movable with reference to each other whereby the outer gripping ends of the jaws are caused to move towards and away from each other.

4. In a device of the kind described, the combination with means for raising and lowering a container, of a pair of movable gripping jaws carried by and movable with said means, and stationary means for causing said jaws to move toward and away from each other as said raising and lowering means moves up and down.

30 35 40 In testimony whereof, we hereunto affix our signatures.

GEORGE A. WILLIAMS.
ROLAND E. HILL.
